UNITED STATES PATENT OFFICE.

ERNEST DE GAY, OF LIVINGSTON HEIGHTS, VIRGINIA, ASSIGNOR TO MODERN DIE AND PLATE PRESS MFG. CO., OF BELLEVILLE, ILLINOIS, A CORPORATION OF ILLINOIS.

RIBBON CLEANER FOR EMBOSsing MACHINES.

Application filed July 7, 1923. Serial No. 650,135.

To all whom it may concern:

Be it known that I, ERNEST DE GAY, a citizen of the United States, residing at Livingston Heights, in the county of Arlington and State of Virginia, have invented a certain new and useful Improvement in a Ribbon Cleaner for Embossing Machines, of which the following is a specification.

10 My invention relates primarily to embossing presses and more particularly to an attachment for embossing machines for cleaning the ribbon employed in embossing processes in removing excess ink from the 15 face of a die.

One of the objects of my invention is to provide a construction of ribbon cleaner which may be mounted upon any construction of embossing machine and interposed 20 between the usual take-up reel on the press and the point where the ribbon is employed to clean the face of the die.

Another object of the invention is to provide a ribbon washing attachment for embossing machines with means for conveniently and quickly threading the ribbon through the washing attachment and effectively removing ink from the ribbon during the impression operations of the embosser.

Another object of my invention is to provide a ribbon washing attachment for embossing presses constructed and arranged to remove excess ink from a wiping ribbon and directly return the ink to the main ink fountain of the embosser to be reused in the embossing process.

A still further object of my invention is to provide a washing attachment for the 40 ribbon of an embossing machine with a supporting frame carrying a plurality of ink scraping devices or knives and ribbon moistening devices with a hinged frame adjacent the supporting frame having a plurality of ribbon guide means for confining the path of movement of said ribbon immediately adjacent said ink scraping and ribbon moistening devices.

A further object of the invention is to 50 provide a construction of removable pan on a ribbon washing attachment for embossing machines which may be quickly inserted or withdrawn from the frame of the attach-

ment for supplying the washing fluid to the ribbon moistening devices carried by the attachment in juxtaposition to the ribbon to be cleaned.

Another object of the invention is to provide a construction of ribbon washing attachment for embossing machines in which the passage of the ribbon through the washer is controlled by the tension take-up force imparted to the ribbon by the storage take-up ribbon roller on the press drawing the ribbon through the attachment and subjecting the same to ink removing processes.

Other and further objects of my invention will be understood from the following specification and by reference to the accompanying drawings, in which:

Figure 1 is an assembly view showing a side elevation of a part of a die stamping press or embossing machine with my ribbon cleaning attachment mounted on the machine; Fig. 2 is a fragmentary view showing the tension take-up roller on the power press which draws the ribbon through the washing attachment; Fig. 3 is a side elevation of my ribbon washing attachment mounted upon the rear of the die table railings of the embossing machine illustrating the arrangement of the mechanism by which excess ink is removed from the ribbon and returned to the main ink fountain ready for reuse in the embossing process; Fig. 4 is a view of the upper portion of the ribbon washing attachment showing the hinged frame which carries the pressure guide rollers opened upwardly or raised to a vertical position to permit the ribbon to be threaded through the washer; Fig. 5 is a plan view of the ribbon washing attachment mounted with relation to the power press; Fig. 6 is a partial sectional view of my washing attachment taken on line 6-6 of Fig. 3; and Fig. 7 is a front view of the hinged frame which carries the pressure guide rollers serving to force the ribbon against the ink removing knives and the moistening and washing rollers.

The present embodiment of my invention has been found to be very practical in construction and successful in operation. The invention contemplates mounting a ribbon washing attachment on the rear of the die table railings of the embossing press and

passing the wiping ribbon immediately after it has been employed in cleaning the embossing die through the washing attachment, removing the ink from the ribbon 5 and storing the ribbon on a take-up tension roller ready for reuse when the supply from the feed roller has become exhausted. The washing attachment comprises a supporting frame consisting of two side plate members carrying all the parts of the washer and detachably connected by a suitable casting with the die table railings of the press. The side plates of the supporting frame are laterally extended at their extremities 15 and provide journals for a plurality of ink scrapers, a washing roller, and a ribbon moistening or guide roller. At the upper extremity, in one corner of the side plate members, I pivot a hinged frame carrying 20 a plurality of pressure guide rollers. The ribbon from the embossing machine is passed over the scraping knives carried by the supporting frame and passed between a pair of the rollers carried by said hinged 25 frame adjacent the pivotal mounting while the hinged frame is opened up away from the scraping knives. When the hinged frame is lowered in position and locked in closed relation to the supporting frame the 30 guide pressure rollers press the ribbon firmly against the ink scraping knives, the moistening roller and the washing roller. The ribbon is drawn under tension through the attachment by the tension take-up roller 35 on the press which rotates intermittently in timed relation to the movement of the die inking roller and successively as the embossing process continues. The attachment is so located on the embossing press that as the 40 ink is removed from the ribbon it drops by gravity action directly into the main ink fountain of the press ready for reuse in the embossing process. A fluid bath is provided 45 for the washing roller and the moistening device carried by the supporting frame. The bath may comprise many different fluids as hereinafter set forth. The pan containing the bath may be quickly inserted adjacent the upper part of the supporting frame immersing a portion of the washing roller. The mounting of the pan is such that it 50 may be quickly withdrawn from the frame.

My invention will now be described in more detail by reference to the accompanying drawings in which numeral 1 indicates the die table railings of any desired construction of power die stamping press. Only sufficient mechanism of the press has been 55 illustrated to clearly set forth the application of my invention. The main ink fountain has been indicated at 2 mounted above the waste pan 3. The ink rollers of the die inking mechanism are driven through the gear train 6, 7 and 8 in mesh with sprocket

wheel 9 which is continuously driven when 65 the press is in operation through chain 10. An inking roller 11 carried by movable frame 12 operates to apply ink to the die successively during the embossing process. The wiping ribbon which is used to remove 70 the excess ink from the face of the die immediately after each inking operation is indicated at 14. This ribbon is usually paper and is normally immediately stored on a take-up roller after the embossing process 75 and then the paper discarded as unfit for use. When a fresh roll of paper must be purchased to replace the used roll, the expense of operation becomes a considerable item. With my invention the same paper 80 may be used a number of times thereby reducing the cost of ribbon renewals.

My attachment is secured to the rear of the die table railings 1 by means of a casting 15 which fits between the rails as indicated at 16. The side plate members 17 and 18 are secured at opposite sides of casting 15 and extend vertically in the rear of the power press substantially perpendicular to the table of the press. The side members 17 and 18 are laterally extended at their extremity forming a supporting frame for the main ink-removing scraper 19, the ink and washing fluid removing scraper 20 and the finishing scraper 21. The several scrapers are all adjustably mounted in the frame by knife holders 22, 23 and 24 respectively so that the angular position of the scrapers with reference to the ribbon may be selected to secure the best results. The supporting frame also carries journals for the main ribbon washing roller 25 and the ribbon moistening or guide roller 26. The fluid bath is contained in the removable pan 27 which is quickly inserted or withdrawn from the supporting frame by a horizontal movement which automatically drops the pan to a sufficient level to enable the top of the pan to clear the lower edge of the washing roller 25. One method by which I accomplish this is by providing pins 28 on the outside walls of the pan 27 which travel in the guides 29 which may be formed when the plates 17 and 18 are cast. Fluid from the pan 27 may be conveyed to the surface of the moistening roller 26 by capillary attraction by means of the absorbing wick 30 arranged so that the lower surface of roller 26 always contacts with the wick and is thereby moistened enabling the roller to serve as a guide for the paper 14 without adhering or sticking to the paper as I have found that it has a tendency to do immediately after the removal of the major portion of the ink from the paper by scraper 19. The amount of washing fluid on washing roller 25 may be regulated by the brush or wiper 31 by which

the depth of the film of washing fluid on the surface of the washing roller 25 is determined.

In order to confine the path of movement 5 of the ribbon 14 against the scrapers and over the moistening roller 26 and the washing roller 25 I hinge the paper adjusting frame and guide 32 at the upper extremity of the support 17 and 18 in the corner indicated at 10 33. The frame 32 may be opened or vertically raised with respect to the supporting frame to enable the paper 14 to be threaded through the pressure guide rollers which are carried by the paper adjusting frame 32. At 15 the front of the frame 32 I provide bushings 34 and 35 which are slidable on rod member 36 to properly align the paper for passage through the washing attachment. A roller 37 is carried by the frame 32 guiding the 20 paper 14 against the knife 19. The major portion of the ink is removed by this operation. My washing attachment is so located with respect to the embossing machine that the ink drops by gravity, as represented at 25 38, into the main ink fountain 2 at 39 ready for reuse in the embossing process. A roller 40 is provided to force the ribbon against the main washing roller 25. Roller 41 is arranged to serve both as a means for forcing 30 the ribbon against the washing roller 25 and also to form a bearing surface cooperating with the scraper 20 to remove the plastic film of ink which has become dissolved in the fluid. Rollers 42, 43 and 44 function to guide 35 the ribbon in position against knife 21 which thoroughly cleans the ribbon of any undesired coating which may be still contained thereon. Roller 45 serves to guide the paper to the tension take-up roller 46. This roller 40 is operated intermittently through chain 47 and gear mechanism 48 to wind up the ribbon as it is used during the embossing process after the ribbon has been cleansed of the ink.

45 The washing fluid may be of various kinds for example alcohol may be used or gasoline employed. Benzine may be used in the bath or ordinary coal oil may be employed. I have observed that coal oil has a tendency 50 to strengthen the fibers of the paper while benzine evaporates quickly and tends to weaken the paper.

While I have described my invention in a certain particular embodiment it is to be 55 understood that various modifications may be made in the details of construction and that I intend no limitations upon my invention other than are imposed by the scope of the appended claims.

60 What I claim and desire to secure by Letters Patent of the United States is as follows:

1. An attachment for embossing machines comprising a pair of side members forming 65 a supporting frame, a plurality of angularly

adjustable knives carried at the extremity of said frame, a ribbon washing roller journaled in said side members, a removable pan carried by said frame for supplying a cleansing fluid to said roller, a hinged frame 70 pivoted to said supporting frame and arranged to be opened or closed with reference to said supporting frame and means carried by said hinged frame for pressing a movable ribbon against said knives and said washing 75 roller for removing coatings of ink therefrom.

2. A ribbon cleaning attachment for embossing machines comprising in combination with the frame of an embossing machine having a wiping ribbon, an attachable frame, ink scraping and washing means carried by said frame, a hinged frame positioned on said first mentioned frame and having means for threading the ribbon 80 through said frame and guiding said ribbon under pressure against said scraping and washing means.

3. A ribbon cleaning attachment for embossing machines comprising in combination with the frame of an embossing machine having a wiping ribbon, an attachable frame, ink scraping and washing means carried by said frame, a fluid bath carried at the extremity of said frame for partially 90 immersing said washing means in said fluid bath, a hinged frame positioned on said first mentioned frame and having means for threading the ribbon through said frame and guiding said ribbon under pressure 95 against said scraping and washing means.

4. A ribbon cleaning attachment for embossing machines comprising in combination with the frame of an embossing machine having a wiping ribbon, an attachable 100 frame, ink scraping and washing means carried by said frame, said means consisting of a plurality of different knives arranged at different levels and a plurality of moistening and washing rollers arranged at different levels, a hinged frame positioned on said first mentioned frame and having means for threading the ribbon through said frame and guiding said ribbon under pressure 105 against said scraping and washing means.

5. A ribbon cleaning attachment for embossing machines comprising in combination with the frame of an embossing machine having a wiping ribbon, an attachable frame, ink scraping and washing means carried by said frame, a hinged frame positioned on said first mentioned frame and substantially extended thereover, a plurality 120 of pressure guide rollers for said ribbon carried on the upper and lower sides of said hinged frame whereby said hinged frame may be raised with relation to said first mentioned frame and said ribbon threaded through said rollers and said hinged frame closed against said first mentioned frame 125 130

forcing said ribbon against said scraping and washing means.

6. A ribbon cleaning attachment for embossing machines comprising in combination with the frame of an embossing machine having a wiping ribbon, an attachable frame, ink scraping and washing means carried by said frame, said frame comprising side members, guide rails carried by said side members and a pan having means cooperating with said guide rails whereby a horizontal and vertical movement may be imparted to said pan to immerse said washing means in a fluid bath contained in said pan and means for passing said ribbon over said ink scraping and washing means whereby ink is removed from said ribbon.

7. A ribbon cleaning attachment for embossing machines comprising in combination with the frame of an embossing machine having a wiping ribbon, an attachable frame, ink scraping and washing means carried by said frame, a hinged frame positioned on said first mentioned frame, a ribbon guide at the extremity of said hinged frame, a roller immediately adjacent said guide on said hinged frame, said roller being positioned opposite one of said ink scraping means on said attachable frame, a moistening roller on said attachable frame behind said scraping means and a plurality of guide rollers on said hinged frame for pressing said ribbon against said scraping and washing means during the passage of the ribbon through said attachment where-

by a coating of ink may be removed from said ribbon.

8. A ribbon cleaning attachment for embossing machines comprising in combination with the frame of an embossing machine having a wiping ribbon, an attachable frame, separate ribbon moistening and washing rollers on said frame, a hinged frame having means for pressing said ribbon against said rollers, said moistening roller being journaled at a higher elevation than said washing roller and serving to meet a particular portion of said ribbon prior to the time said portion reaches said washing roller whereby coatings on said ribbon may be dissolved and removed.

9. A ribbon cleaning attachment for embossing machines comprising in combination with the frame of an embossing machine having a wiping ribbon, an attachable frame, ink scraping and washing means carried by said frame, a ribbon guide frame journaled at one corner of said attachable frame said guide frame having a pair of polygonal side members, pressure guide rollers journaled between said members, said guide frame having a greater length and shorter width than said attachable frame whereby said guide frame may be closed upon said attachable frame and said ribbon pressed against said scraping and washing means whereby ink may be removed from said ribbon during the passage of the ribbon through the machine.

ERNEST DE GAY.
